UNITED STATES PATENT OFFICE.

WALTER GERARD, OF ST. BERNARD, AND JOHN H. LAWRENCE, OF BOND HILL, OHIO.

WIRE-COUPING.

SPECIFICATION forming part of Letters Patent No. 575,641, dated January 19, 1897.

Application filed November 23, 1896. Serial No. 613,092. (No model.)

To all whom it may concern:

Be it known that we, WALTER GERARD, of St. Bernard, and JOHN H. LAWRENCE, of Bond Hill, Hamilton county, State of Ohio, citizens 5 of the United States, have invented a certain new and useful Wire-Coupling; and we do declare the following to be a clear, full, and exact description of the invention, such as will enable others skilled in the art to which it app 10 pertains to make and use the same, attention being called to the accompanying drawings, with the reference-numerals marked thereon, which form a part of this specification.

This invention relates to a device or coupling intended to be used for the purpose of obtaining connection between the ends of two wires. These ends may be the ends of two different wires or they may be ends of a wire separated by fracture or otherwise.

20 The device is more particularly intended to reëstablish connection between two fractured ends of a broken wire and, being constructed to permit such connection to be made rapidly and without the aid of any tool, it is emi 25 nently well adapted to serve as a coupling to reëstablish connection, electrical as well as mechanical, between two fractured ends of broken trolley-wires, as used with electric-railway systems. Most devices now used for 30 such purpose require considerable time until placed in position, which is very objectionable, owing to the interruption and extended delay of travel. This objectionable feature is modified by our construction in a manner 35 that the time required to make the connection is reduced to the lowest possible minimum.

In the following specification and particularly pointed out in the claims is found a full 40 description of the invention, its manner of use, parts, and construction, which latter is also illustrated in the accompanying drawings, in which—

Figure 1 is a longitudinal central section of the coupling, showing one of the wires, the 45 one to the right, in position, while the other wire is shown approaching a similar condition to complete the connection. Fig. 2 is an elevation of the device, showing the connection completed. Fig. 3 is an elevation at right angles to the one shown in the preceding figure. Fig. 4 is a cross-section on line 4 4 of Fig. 1,

and Figs. 5 and 6 are detail views of the locking-jaws.

7 is sleeve of suitable metal, which when the device is used for uniting electrical wires 55 should be also a good electrical conductor. This sleeve has two longitudinal bores 8 8, which start from each end inwardly and are centrally in line with each other. The outer open ends of these bores correspond approximately with the size of the wire, permitting 60 easy entrance of the same, while toward their inner ends they widen out in one plane, as best shown in Fig. 1. The size of the other dimension, that is, the one in a plane at right 65 angles to the plane first mentioned, remains nearly the same as at the mouth, as best shown in Fig. 4 and in dotted lines in Fig. 3. For each bore there are provided two jaws 9 9, serrated on their inner opposite faces, which 70 are introduced through openings 10 10, and are intended to hold between them one of the ends of the wires to be connected, as shown at the right half of Fig. 1. In order to prevent these jaws from dropping out of place 75 and to hold them at the same time in a position which permits the insertion and connection of the wire ends in the proper manner, they are connected to or form part of a spring 80 11, which is so shaped and bent as to hold 80 them in the proper and requisite position and as shown in the left part of Fig. 1. Fig. 5 shows also this spring and the tendency of its action before insertion.

The sizes of the two bores are equal where 85 the coupling is used for reconnecting the fractured ends of a broken wire; but it might also be used to connect the thicker to a thinner wire, in which case the size of the bores would correspond to the different size of the 90 wires.

For connecting the ends of a broken wire they are one of each introduced fully into one of the bores, as shown in Fig. 1, where wire 12 is shown while entering. During this 95 inward movement it passes between the serrated surfaces of the two jaws and forces them apart, the spring readily permitting such, but holding the jaws closely against the wire. When in the final position, as 100 shown for the other wire 13, it pulls, by reason of the tension in the wires, against the

sharp edges of the teeth and causes the jaws to slide outwardly into the narrower part of the bore. The flat backs of the jaws come finally in contact with the converging walls

5 14 of the bores, whereby under the continuing pull the teeth are caused to dig or bite into the wire. The bur of metal forced up in front of the teeth is sufficient to keep the wires in place.

10 In practice the sleeve is pushed on one of the wire ends, and then the sleeve with such end is brought opposite the other wire end, and the latter is pushed into the former. The final connection after once in position is instantaneous, inasmuch as the jaws take hold as soon as the wire is let go and has with the jaws slid slightly outwardly into the narrower part of the bore. The aforesaid spring accelerates this act.

15 20 To obviate all delays and permit the manipulation to be performed as rapidly as possible, a stop by a division-wall 15 at the inner meeting ends of the bores is provided, which prevents the first wire from being 25 pushed in too far or into the other bore.

As the pull of the wires imparts to the jaws a constant tendency to advance into the narrowing part of the bore, it is evident that an increasing pull increases this tendency, 30 whereby as a necessary consequence the teeth act with augmented pressure against the wires, making the connection only firmer.

The sleeve should be tapering toward its outer ends to facilitate passage of the trolleys.

35 40 There is hardly any appreciable wear on these couplings, and they may be recovered for reuse in case ever a line is taken down for any reason whatsoever. For such purpose the end of a wire is pushed inwardly toward wall 15, which may be readily done, since there is no strain on it then. This movement, being contrary to the action of the teeth and and into the broader part of the bore, causes the engaging parts to yield readily and come 45 apart. A pointed implement 16 is then introduced through an opening 17, which latter is so located as to cause the point of the former to come down in front of the bight of spring 11, and whereby this latter, with jaws 50 9, is prevented from following the wire end when the latter is now pulled out.

It is evident that one tooth on each jaw might, under certain conditions, be sufficient to hold a wire in place, but we prefer a plurality of them. It is also obvious that only one jaw might be used in a bore, provided one of the walls 14 is made straight, that is, parallel with the wire, and which would be simply using half of our arrangement. By using 60 two jaws, however, one at each side of the wire, the strain and stress are equalized and the connection becomes firmer and more reliable.

Having described our invention, we claim 65 as new—

1. A wire-coupling consisting substantially

of a sleeve having two bores, one entering at each end and both centrally in line with each other, each of said bores being substantially of one dimension in one direction or plane 70 while in the other they become wider, forming two walls 14 diverging toward the inner ends of the sleeve and two serrated jaws with flat backs in each bore occupying, when a wire end is introduced, the spaces at each 75 side of the latter and between it and walls 14 against which latter they lie with their flat backs.

2. A wire-coupling consisting substantially of a sleeve having two bores, one entering at 80 each end and both centrally in line with each other, two serrated jaws in each bore held therein prior to their engagement with a wire end and in proper position for the purpose of enabling such engagement by spring-pres- 85 sure and openings in the sleeve to permit introduction of these jaws.

3. A wire-coupling consisting substantially of a sleeve having two bores, one entering at 90 each end and both centrally in line with each other, each of said bores having two walls 14, converging toward the outer ends of the sleeve and two serrated jaws in each bore occupying, when a wire end is introduced, 95 the spaces at each side of the latter and between it and walls 14, said jaws held in place prior to their engagement with a wire end and in proper position for the purpose of enabling such engagement by spring-pressure and openings in the sleeve to permit introduction of these jaws.

4. A wire-coupling consisting substantially of a sleeve having two bores, one entering at 100 each end and both centrally in line with each other, each of said bores having two walls 14, 105 converging toward the outer ends of the sleeve and two serrated jaws in each bore occupying, when a wire end is introduced, the spaces at each side of the latter and between it and walls 14, said jaws connected to 110 or forming part of a spring 11 whereby they are held in a position substantially parallel and with the teeth opposite each other.

5. A wire-coupling consisting substantially of a sleeve having two bores, one entering at 115 each end and both centrally in line with each other, each of said bores having two walls 14, converging toward the outer ends of the sleeve and two serrated jaws in each bore occupying, when a wire end is introduced, 120 the spaces at each side of the latter, between it and the walls 14 and openings 17 near the inner ends of the bores for the purpose described.

In testimony whereof we hereunto affix our 125 signatures in presence of two witnesses.
